UNITED STATES PATENT OFFICE.

JOHN T. JONES, OF IRON MOUNTAIN, MICHIGAN, ASSIGNOR TO NEW METALS-PROCESS COMPANY, OF CHICAGO, ILLINOIS, A CORPORATION OF ILLINOIS.

BOILER.

1,147,326.

Specification of Letters Patent. Patented July 20, 1915.

Application filed March 28, 1914. Serial No. 828,000.

To all whom it may concern:

Be it known that I, JOHN T. JONES, a citizen of the United States, residing at Iron Mountain, in the county of Dickinson and State of Michigan, have invented a new and useful Improvement in Boilers, of which the following is a specification.

This invention relates particularly to boilers, such as steam-boilers; and the primary object is to provide a simple, highly-efficient boiler.

The invention is illustrated in its preferred embodiment in the accompanying drawings, in which—

Figure 1 represents a side elevational view, partly in section, of a boiler constructed in accordance with my invention; Fig. 2, an enlarged broken, sectional view taken, as indicated, at line 2 of Fig. 1 and showing the connection between one of the water-tubes and a head with which it connects; Fig. 3, a transverse sectional view of the boiler, the view taken as indicated at line 3 of Fig. 4; and Fig. 4, a horizontal sectional view taken as indicated at line 4 of Fig. 3.

In the construction illustrated, A represents a furnace-body provided with a smoke-stack A'; and B, B', two series of water-tubes dividing the interior of the furnace into an inner coking-chamber C and outer complete-combustion chambers C'. The furnace preferably has the curved top 1 which is provided with a charging-device 2 through which coal or wood may be introduced. The series of water-pipes are connected, respectively, at their upper ends with large horizontal heads or pipes 3 which are separated from each other a sufficient distance to enable the fuel to be charged into the internal chamber C. The pipes B, B' are respectively connected at their lower ends with large horizontal base-pipes 4 which are close enough together to support the fuel but are spaced to permit the coke to be discharged. The pipes B are preferably flattened or made oval and are bowed outwardly at their central portions so that the chamber C, which is bounded laterally by the two series of pipes B, B', is expanded at its central portion, the purpose being to allow the charge of coal, whose upper surface is indicated by the lines 5, to be partially supported by the lower portions of the series of pipes. A longitudinal central

pier or abutment 6 is disposed beneath the space 7 which separates the lower pipes 4, being separated from the pipes by spaces 8, sufficiently large to allow the coke to feed out onto the grates 9 which flank the central longitudinal base-wall 6. Below the grates are provided lateral doors 10 fitted with air-registers 11. Above the grates are provided doors 12 through which a poker may be thrust to stir the fire. The grates 65 are provided with longitudinal shaker-bars 9a. Air-admission devices 13 are connected with the lateral walls of the furnace below the lateral complete-combustion chamber C'. Air is admitted to the upper portion 70 of the coking-chamber C through the twyers 14 provided with air-regulating devices 15. The ends 16 of the furnace are shown removable, to enable the tubes and pipes to be cleansed when necessary. The curved 75 vertical pipes of each series B, B' are disposed side by side and close together, so that the chambers or flues C' are formed between the vertical series of pipes and the side-walls of the furnace.

In the operation of the furnace, the fuel, such as bituminous coal, is charged through the device 2 and falls between the upper horizontal pipes 3 into the central chamber C. By means of a down-draft of air furnished by the twyers 14, a coking operation is carried on in the central chamber. The gases thus formed pass upwardly through the flues C', and complete combustion is effected by air admitted through the tubes 13. 85 The coke gravitates downwardly between the pipes 4 and is deflected through the passages 8 and is consumed on the grates 9, air being supplied to the grates through the registers 11.

It will now be understood that by means of the improved construction it is possible to completely burn the hydro-carbons and carbon monoxid produced in chamber C as these combustible gases pass through the 100 flues C'; also that the coke may be burned on the grates 9, and that a smokeless furnace is thus afforded. Where the boiler is used as a steam boiler, the upper pipes 3 may contain steam, while the pipes B and 105 the pipes 4 may be filled with water.

The foregoing detailed description has been given for clearness of understanding only, and no unnecessary limitations should be understood therefrom, but the appended 110

claims should be construed as broadly as permissible in view of the prior art.

What I regard as new and desire to secure by Letters Patent is—

- 5 1. In a boiler, the combination of a central coking-chamber having at its upper end a central passage for the introduction of fuel, means for supplying air to the upper portion thereof, water-legs at the sides of
10 the coking-chamber, up-draft flues between said water-legs and the adjacent walls of the furnace, a grate in the base-portion of the furnace beneath each updraft flue with means for drawing coke to the grates as it
15 is formed, and means for admitting air to the lower portions of the updraft flues.
2. In a boiler of the character set forth, the combination of a furnace provided at its upper portion with a fuel-charging device, water-legs spaced in said furnace at a distance from the lateral walls and separated from each other, thus affording a central coking-chamber between the water-legs, and up-draft flues outside the water-legs,
25 said coking-chambers and flues being open at their upper and lower ends, means for supplying air to the upper portion of the coking-chamber, grates in the base-portion of the furnace beneath the up-draft flues,
30 means for deflecting coke, as formed, to the grates, and means for supplying air to the base-portions of the up-draft flues.
3. In a boiler of the character set forth, the combination of a furnace-body, two
35 series of outwardly-bowed water-tubes therein spaced with relation to the side walls and with relation to each other, thus affording a central coking-chamber and flanking up-draft flues, means for charging fuel into
40 the upper portion of the central coking-chamber, means for supplying air to the upper portion of the coking-chamber, grates at the lower portion of the furnace-body beneath the up-draft flues, and means for
45 admitting air to the up-draft outer flues flanking the water-tubes.
4. In a boiler of the character set forth,

the combination of a furnace-body, two series of outwardly-bowed water-tubes therein spaced with relation to the side walls 50 and with relation to each other, thus affording a central coking-chamber, means for charging fuel into the upper portion of the central coking-chamber, means for supplying air to the upper portion of the coking-chamber, grates at the lower portion of the furnace-body, means for admitting air to the up-draft outer flues flanking the water-tubes, and means for admitting air below 55 said grates.

5. In a boiler of the character set forth, the combination of a furnace-body having curved lateral walls and a curved top wall, two series of vertical curved water-tubes spaced with relation to the furnace-walls 60 and affording between them a central coking-chamber, heads connecting the tubes of each series at their upper ends, said heads spaced to admit fuel between them, means for admitting air to the upper portion of 65 the coking-chamber, grates at the lower portion of the furnace, and means for admitting air to the lower portion of the furnace.

6. In a boiler of the character set forth, the combination of a furnace-body, a pair 75 of horizontal heads in the upper portion thereof, a pair of horizontal heads in the lower portion thereof, curved water-tubes connecting said heads, said tubes spaced to afford between them and the lateral walls 80 up-draft flues and said series of tubes affording between them a central coking-chamber, means for charging fuel between the upper heads, means for admitting air to the upper portion of the coking-chamber, 85 a central base-wall below the space between said lower heads, grates flanking said central base-wall, and means for admitting air to the lower portion of the furnace.

JOHN T. JONES.
